METHOD OF KNITTING

Oscar Fregeolle, Central Falls, R. I., assignor to
Hemphill Company, Central Falls, R. I., a corporation of Massachusetts

Application February 8, 1944, Serial No. 521,488

9 Claims. (Cl. 66—43)

This invention relates to a new and useful improvement in a method of knitting on knitting machines of the circular, independent needle, type and in fabric produced by that method. Although the method may be performed and the fabric produced on various kinds of knitting machines of the circular type the well-known Banner machine is peculiarly suited for the purpose and, consequently, has been selected for illustration and description in connection with this invention.

Heretofore difficulty has been encountered, particularly in the knitting of hosiery, in securing a uniform and symmetrical loop structure. It frequently happens that many of the loops are tilted from the perpendicular and that one side of a loop is different from the other. Although these peculiarities are minute, they nevertheless impair the over-all appearance of the fabric, particularly of the finer gauges in which substantially perfect loop structure is essential.

The defects mentioned are particularly noticeable in split fabric produced by reciprocatory knitting because the tilt of the loops tends to follow the direction of knitting so that the loops of one course tilt in one direction whereas, in the next course, the loops tilt in the other thus magnifying the defect and producing the so-called "washboard" effect.

When a decorative stripe or other pattern is incorporated in a fabric, by the method known as wrapping, for example, the same lack of uniformity and symmetry of loop structure is encountered particularly at the edges. Since such patterns are usually of a different color or colors than the adjacent fabric such defects are very conspicuous. Furthermore, because true wrapping has heretofore been done only in rotary knitting or in one direction, i. e., in alternate courses, during reciprocatory knitting, so that a float of the wrap yarn extends from the end of the wrap in one course to the beginning of the wrap of the next course, there is an unavoidable variation in yarn tension which results in a tight loop at one edge of the wrap and a relatively loose loop at the other so that the outline of one edge is sharper than that of the other.

In reciprocatory knitting, this same difficulty has existed and also no way has been known to insert a wrap in every course. Wrapping has been limited to every other course, those courses being the ones in which the needles are moving in the same direction as during rotary knitting.

By this invention not only is the body fabric greatly improved both in rotary and reciproc-

catory knitting but also the wrap so that the design has a clearer color, a sharper outline and a much more attractive appearance. This results not only from the new method of knitting but also from the fact that in reciprocatory knitting the structure of the wrap is new and improved. The long floats from the finish of the wrap in one course to the beginning of the wrap in the next course are eliminated and the two edges of the wrapped area are of the same construction. The loops are formed under substantially the same tension so that the appearance of the two edges is the same instead of noticeably different. In addition, the leg and instep are knitted on the auxiliary side of the machine, in accordance with the present and best practice, since no yarn change is then required. These parts are wrapped by yarn also fed at the auxiliary side of the machine instead of at the main side as heretofore and, most important, successive courses of the reciprocatorily knit instep may be wrapped instead of alternate courses only which has been the limit of possibility in the past. Furthermore, the area which can be wrapped includes the entire instep regardless of its width in relation to the sole instead of being limited as heretofore to a few wales adjacent the edges of the sole.

The mechanism selected for the purpose of explaining the invention is that of the Banner type of circular, independent needle, knitting machine which is too well-known to require detailed description herein. A few of its parts are shown in the drawings which are also illustrative of reciprocatory knitting:

35 Fig. 1 illustrates diagrammatically a carrier ring, the adjustable wrap yarn horns, the wrap spindle, the body yarn feeder, etc., and four steps in the process of wrapping in counter-clockwise direction:

40 Fig. 2 is a diagrammatic illustration of the relative positions of the two wrap yarn horns when the needles are moving in the direction assumed in Fig. 1;

45 Fig. 3 is a view similar to Fig. 1 when the needles are moving in clockwise direction;

Fig. 4 is a view similar to Fig. 2 illustrating the relative positions of the two wrap yarn horns under the conditions of Fig. 3;

50 Fig. 5 is a diagrammatic view illustrating a needle and sinker before the wrap yarn is taken by the needle;

Fig. 6 is a diagrammatic view illustrating a sinker and a needle and other associated parts 55 as the needle is about to take a wrap yarn;

Fig. 7 is a similar view when the needle is about to take the main or body yarn;

Fig. 8 illustrates the manner in which the two yarns are drawn over the back of the sinker;

Fig. 9 illustrates a further step when the needle has risen so that the two yarns are over its latch;

Fig. 10 illustrates the feeding of the wrap yarn to a needle in the following course which is knit in the reverse direction, the previously fed and knit wrap and body yarns being shown in the throat of the sinker;

Figs. 11 and 12 are views of the needle and two adjacent sinkers illustrating the manner in which the body and wrap yarns of the course relating to Figs. 1 to 5 are transferred from the backs to the throats of the sinkers over the tops of the nibs;

Fig. 13 illustrates the taking of the body yarn for the second mentioned course and also shows as in Fig. 7 its relative position with respect to the wrap yarn;

Fig. 14 illustrates casting off of the loops of the first course by the throats of the sinkers acting directly against the yarns of that course and also the yarns of the succeeding course over the backs of the sinkers;

Fig. 15 is a diagrammatic illustration of a split foot stocking having a wrap pattern in the leg and instep;

Fig. 16 is an accurate reproduction of an enlarged projection of actual fabric having a five needle wrap knitted in a rotary manner as, for example, in the leg of a stocking, by the method of this invention;

Fig. 17 is a similar reproduction of fabric including a five needle wrap in every course produced by reciprocatory knitting;

Fig. 18 is a similar reproduction of fabric including a one needle wrap in every course also produced by reciprocatory knitting;

Fig. 19 is a developed view showing the paths followed by the jacks and needles in rotary or counter-clockwise reciprocatory knitting;

Fig. 20 is a similar view illustrating the paths followed by the jacks and needles during clockwise reciprocatory knitting; and

Fig. 21 is a view of the cam plate which controls the operating of the wrapping means.

As shown in Figs. 1 and 3 the machine is provided with the usual rotatable needle cylinder indicated by the broken lines 1, complement of needles 2, and carrier ring 3 equipped on the main side of the machine with the usual yarn levers 4. On the auxiliary side is another yarn lever 5, mounted on the underside of carrier ring 3 in such a way that it can be moved outwardly radially when the feeding of the body yarn 6 is momentarily discontinued as when knitting the heel and toe, and can be swung on a pivot to move yarn 6 completely away from the knitting field whenever the feeding of the yarn is discontinued for longer periods. The mechanisms for imparting these movements to auxiliary yarn lever 5 are not shown since they form no part of this invention.

The machine is also provided with a wrap spindle 7, preferably provided with a plurality of feeds, and two wrap yarn horns 8 and 9 for guiding the wrap yarn as will be explained later. Horns 8 and 9 are each provided with rollers 10 sliding in a vertical guide 11 in the inner end of a bracket 12 which is attached to an arcuate ring 13 adapted to swing through a definite arc on a suitable guide ring 14 of carrier ring 3. The swinging of arcuate ring 13 is controlled from the

sinker head friction ring (not shown), which is also capable of swinging through a certain arc, by means of a connection 15 attached to the sinker head friction ring (not shown) and engaging fork 16 on arcuate ring 13. A pin 17 which may be the pivot of a roller 18 projects into a camway 18 in a stationary arcuate plate 19 (Figs. 1, 3 and 21). There are two opposite camways 18, one for each horn, so that when ring 13 is rotated in one direction horn 8 will be lowered and horn 9 raised and vice versa by the movement of pins 17 along camways 18. There is also the usual binder plate 20.

The leg and instep of the stocking are knit on the auxiliary side of the machine as is now customary so that the same yarn can be used throughout and uniformity of yarn and stitch in these parts assured. The leg is knit in a rotary manner and the instep and foot by reciprocatory knitting.

When knitting the leg by rotary knitting yarn 6 is fed to the needles by means of lever 5 on the auxiliary side and is knit on that side, all of the needles traversing the path 21 (Fig. 19) and knitting at cam 22.

If this part of the stocking is to be provided with a wrap pattern the wrap yarn 23 is fed over horn 8 which is in its low position (Fig. 2) to the needle or needles which are to be wrapped by wrapping spindle 7 one finger of which has been swung out by suitable mechanism so that its eyelet 24 lies outside the needle circle as shown in Fig. 1. Wrap spindle 7 rotates one to one with needle cylinder 1 as usual.

The needles to be wrapped have been selected and elevated to a position 25 (Fig. 19) higher than the usual yarn receiving position, by a suitable selector means 26 and master cam 27 operating upon jacks, such as 28, to receive the wrap yarn 23. When the wrap yarn has been fed to the selected needles, the finger moves back to a position inside the needle circle indicated at 29 in Fig. 1, the wrap yarn dropping off the end of horn 8 as shown at 30. Upon further rotation of the needle cylinder and wrap spindle eyelet 24 assumes a position 31 the wrap yarn now passing under binder plate 20 as indicated at 32 and under horn 9. As the rotation of the cylinder and wrap spindle continue eyelet 24 continues to move to a position such as 33 and the wrap yarn, extending to the last needle wrapped, also continues to swing around under binder plate 20 as indicated at 34 and so on until the cycle is completed.

Although horn 8 has been in its low position shown in Fig. 2, as above stated, this position, as a matter of fact, may be considerably higher than usual so that wrap yarn 23 is held high up on the needles and moves into the hooks earlier than usual and, consequently, is positively positioned above the body yarn on the needles. Just as a wrap yarn 23 drops off the end of horn 8 body yarn 6 is fed to the needles by yarn lever 5 which, since it is mounted on the underside of the carrier ring feeds the body yarn to the needles below wrap yarn 23 and at a much lower angle than the wrap yarn was fed by wrap spindle 7 and horn 8. The feeding of the wrap yarn high on the needles and above the body yarn leaves plenty of room for feeding the body yarn well above the latch pivots so that there is no danger that the yarn will be cut or frayed by the closing of the latches.

The feeding of the body and wrap yarns to the needles is also illustrated by Figs. 5 to 9. In

Fig. 5 is shown a needle 2 and sinker 38 before feeding of any yarn. In Fig. 6 needle 2 is in the elevated position 25 (Fig. 19) to receive wrap yarn 23 as fed by wrap spindle eyelet 24 over horn 8. In Fig. 7 the needle 2 has descended to a lower position for the reception of the body yarn 6 as fed by yarn lever 5 prior to knitting. It will be noted that now wrap yarn 23 is in the hook of the needle and passes over a smaller portion of horn 8 and that body yarn 6 is fed to the needle considerably below the wrap yarn. In Fig. 8 the needle has descended still further and has drawn the two yarns over the sinker. However, instead of drawing these yarns in the throats 36 of the sinkers in the usual way the sinkers have been moved inward sooner and further so that the yarn is drawn over the backs 37 of the sinkers. In Fig. 9 the needle has risen again so that the yarn loops are now on the latch. Thereafter, the usual cycle is completed until the needle has again assumed the position shown in Fig. 5 the sinkers meanwhile being drawn out so that their sinker loops have been transferred from the backs to the throats of the sinkers over the nibs 38.

For the next course the wrap and body yarns 23 and 6 respectively are again fed to the needles and knit in the manner just described.

When the change is made from rotary to reciprocatory knitting as, for example, at the beginning of the high-heel, the wrap and body yarns continue to be fed and knit as above described by the instep needles when the needles are moving in counter-clockwise direction. When knitting in the other or clockwise direction the method is similar but in this instance horn 8 has been raised and horn 9 lowered and shifted as shown in Figs. 3 and 4 by means of the mechanism already described and wrap yarn 23 is fed over horn 9 instead of horn 8 and on the other side of needles 2 as shown in Figs. 3 and 10. Then sinkers 35 are drawn out so that the previously formed loops are transferred from the backs to the throats of the sinkers over the nibs as shown in Figs. 11 and 12. Then instep yarn 6 is fed to the needles by yarn lever 5 as shown in Fig. 13 after which the yarns are drawn over the backs of the sinkers which have been again moved inwardly far enough to make this possible and the knitting cycle completed.

When the machine reverses again to knit the next course in counter-clockwise direction horn 9 is again raised and horn 8 lowered and swung into operative position and the feeding and knitting of the wrap and body yarn proceeded with as originally described. Yarn lever 5 and wrap spindle 1 are so positioned on the auxiliary side that both the wrap and instep yarns are fed to the long butt needles including, of course, any short butt needles which have been added to the long butt group, at the same relative points regardless of the direction in which the needles are moving as shown in Figs. 1 and 3.

By feeding in this way and by using the two horns 8 and 9 working in alternation it becomes possible for the first time to feed and knit wrap yarns in every course of the instep during reciprocatory knitting and thus to provide in the instep section a continuous pattern similar to that usually included in the leg.

Of course to do this, means must be provided for selecting the needles to be wrapped in each direction of reciprocation. This is done by means of jacks operating upon the needles under the control of appropriate selectors. For exam-

ple, when knitting in counter-clockwise direction selector 26 (Fig. 19) and master cam 27 may be utilized to elevate jacks and, through them, the desired needles to wrapping position 25 whereas when wrapping in clockwise direction a similar selector 39 and master cam 40 may be utilized to elevate the needles to be wrapped to the equivalent position 41 as shown in Fig. 20 after which the instep needles will knit at cam 42 in clockwise direction and cam 22 in counter-clockwise direction. Of course, the remaining needles are simultaneously knitting the foot of the stocking at cam 44 or 43 as the case may be at the main side of the machine following present split foot practice.

As previously stated the sinkers are so manipulated that at the auxiliary side of the machine the yarns are drawn over their backs instead of their throats and subsequently the loops so drawn are transferred from the backs to the throats over the nibs. This is illustrated by Figs. 11 and 12. These loops are finally cast off from the needles after the corresponding loops of the next course have been drawn. This is accomplished by projecting the sinkers inwardly so that their throats engage with these previously formed sinker loops as shown in Fig. 14. In this figure these sinker loops are indicated by the numerals 23 and 6 by which the wrap and body yarns have been identified throughout this description and the newly formed loops of these same yarns are indicated by the numerals 23' and 6' respectively. As will be seen the newly drawn yarns 23' and 6' resting on the backs of the sinkers are not affected in any way by the engagement of the previously formed loops 23 and 6 with the throats of the sinkers.

The drawing of the loops over the backs of the sinkers and their subsequent transference to the throats over the nibs and the casting off from the needles of these loops without engaging the newly formed loops have a surprisingly beneficial effect upon the shape and uniformity of size of the loops apparently for the following reasons. When the needle loops pass from around the latches of the needles to the shanks they hang somewhat loosely upon the shanks because this part of the needle is smaller. However, when the sinkers are retracted so that the loops are caused to pass from the backs to the throats over the nibs each sinker loop receives a slight tug which tightens the adjacent needle loops around the shanks of the needles. In this way they are brought to substantially the same size. When the needles descend to cast off these loops the loops must, of course, pass again over the latches. In so doing they are slightly stretched but because they have already been equalized this stretching is substantially the same for each loop. This tightening and stretching of the needle loops in this equalizing way has a similar effect upon the adjacent sinker loops so that both the needle and sinker loops are straightened and equalized in size to a degree which is very evident in the finished fabric. Furthermore, the fact that the sinkers when moving in to cast off loops from the needles engage only with the comparatively stable loops of the previous course which are to be cast off and not at all with the unstable newly formed loops, leaves the newly formed loops undisturbed. This is far from the case when casting off involves the engagement of the sinkers with the newly formed loops also as is inevitable when the loops are drawn in the throats

of the sinkers in accordance with previous practice.

These beneficial results are also shared by the loops of the wrap pattern. In the case of a single needle wrap the wrap yarn does not make contact with the sinkers during casting off. However, the character of the wrap benefits greatly from the fact that the underlying body loops are straight and uniform and unaffected by the casting off process so that wrap yarn loops are more exactly positioned upon the body yarn loops. Where the wrap extends across more than one needle the wrap yarn pass through the same process as the body yarn, as clearly illustrated by Figs. 11, 12 and 14, and consequently, benefits directly and to the same extent.

Figs. 16, 17 and 18 are tracings from actual projections of hosiery fabric knitted in accordance with this invention. Fig. 16 illustrates circularly knit fabric with a five needle wrap. Fig. 17 illustrates reciprocatorily knit instep fabric with a five needle wrap in every course. Fig. 18 also represents reciprocatorily knit instep fabric with a one needle wrap. It will be seen that the body yarn loops not only of the circularly knit fabric 45 but also of the reciprocatorily knit fabric 46 are substantially symmetrical in shape and of the same size and also are in alignment so that the wales are straight and well defined. In the reciprocatorily knit fabric of Figs. 17 and 18 the "washboard" effect is practically eliminated.

The same improved characteristics also appear in the loops and wales of the wrap. Also in these parts the loops forming the edges of the wrapped area are normal in shape whereas heretofore one edge has been extremely tight giving the appearance of a straight line rather than a series of loops whereas the other edge has been extremely loose and, consequently, irregular in outline.

In the leg or circularly knit parts of the stocking the wrap, with the exception of the improvements in the shape, size and alignment of the loops mentioned above, has the same general characteristics as formerly. The same float extends from the end of the wrap in one course to the beginning of the wrap in the next as shown at 47 in Fig. 16. However, there is an improvement in the fabric with respect to this float. Heretofore the tension unavoidably imposed on the wrap yarn between the end of the wrap in one course and the beginning of the wrap in the next course has tended to pull the wrap wales together so that a slight outward bulging of the wrap area is caused, the edge loops drawn inwardly and the alignment of the wrap wales and the shape of the loops in those wales impaired. The manner in which the loops are drawn and subsequently manipulated by the method of this invention produces a flat wrap in which the shape and arrangement of the loops, including the edge loops, are normal.

In the reciprocatorily knit parts of the stocking, such as the instep, the long floats such as 47 in Fig. 16 heretofore characteristic of wrapped areas are entirely eliminated. Since the wrap is made in successive courses the wrap in one course begins at the same end that the wrap in the preceding course ended. Therefore, the wrap yarn instead of being carried all the way across the wrapped area is simply carried from the final loop in one course, 48 in Fig. 17, for example, directly up to the beginning loop of the wrap of the next course, say 49 in Fig. 17. Therefore, the problems of tension etc. caused by the long

floats of the wrap are eliminated and the loops at each edge of the wrap area are substantially the same in construction and appearance. This is particularly important in a single needle wrap such as shown in Fig. 18 since any defect in a narrow pattern such as this is very noticeable. As will be seen in Fig. 18 the wrap yarn extends, first on one side and then on the other, from the last loop 50 of one course directly to the corresponding loop 51 of the succeeding course forming a tight substantially symmetrical wale of decidedly improved appearance. The edge construction of wider wrap patterns such as that shown in Fig. 17 is the same, the only difference being that other wrap loops intervene between the edge loops. Therefore, these wider patterns also have a straighter, better looking, outline.

It is hardly necessary to say that wrapping in successive courses during reciprocatorily knitting, which is made possible for the first time by this invention, greatly improves the appearance and extends the possibilities of wrapping in areas knit in this way and is a distinct advance in the knitting art. It is almost as important that these improvements are brought about by easily made changes in the usual knitting methods and knitting machines.

Although this description has been predicated upon the assumption that the loops are drawn over the backs of the sinkers this is not essential insofar as wrapping in consecutive courses of reciprocatorily knit fabric is concerned. If one is willing to accept the less perfect fabric produced by drawing the loops in the throats of the sinkers in the usual manner the entire fabric can be made and wrapped in this way. The sinkers instead of being moved in earlier and further so as to take the yarns over their backs would be moved in at the normal time and to the normal distance to receive the yarns in their throats. This would involve a change in the sinker cams which would be recognized and could be carried out by anyone skilled in the art, otherwise the knitting of the fabric performed in the same way as described herein.

In this description it has been assumed that the heel, sole and toe portions which are, of course, knit on the main side of the machine have been knit in the usual manner the yarn being drawn in the throats of the sinkers as usual. If desired, these portions of the stocking might also be knit by the method of this invention the yarn being drawn over the backs of the sinkers but, since these parts are comparatively inconspicuous, they are usually knit in the conventional way so as to avoid unnecessary complication and alteration of the machine.

If color within color effects are desired in the wrapped areas they may be included by following in general the well-known procedure for producing such effects. However, by modifying the method to conform to that of this invention the areas having the additional color or colors will be benefited in construction and appearance to the same extent as the other areas. Also the inside of the fabric will be improved in that in the reciprocatorily knit portions the long floats will be absent the only floats remaining being the relatively short ones between different parts of the same pattern wrapped by the same finger of the wrap spindle.

As is well known, a fashioned or shaped stocking blank or other fabric can be knit in a reciprocatorily manner on a circular knitting machine by varying the number of needles knitting.

By this invention any part of it may be provided with wrap patterns in consecutive courses which would be free of floats of any substantial length as explained above in connection with the reciprocatory knitting of the foot.

I claim:

1. A method of knitting upon a circular, independent needle, knitting machine which includes the steps of drawing a wrap yarn and a body yarn over the backs of sinkers and through the needle loops of a previous course casting off the previously formed needle loops by engaging the sinkers with the intervening sinker loops only and causing the sinker loops to pass from the backs to the throats of the sinkers over the tops of the nibs said steps occurring in each direction of reciprocatory knitting.

2. A method of knitting upon a circular independent needle, knitting machine which includes the steps of drawing a wrap yarn and a body yarn over the backs of the sinkers and through the needle loops of a previously knit course casting off the previously formed needle loops by engaging the sinkers with the intervening sinker loops only, tightening the newly formed needle loops and stretching the newly formed sinker loops by causing the newly formed sinker loops to pass from the backs to the throats of the sinkers over the tops of the nibs, said steps occurring during each direction of reciprocatory knitting.

3. A method of knitting hosiery fabric upon a circular, independent needle, knitting machine which includes the steps of drawing a wrap yarn and a body yarn over the backs of sinkers and through the needle loops of a previous course casting off the previously formed needle loops by engaging the sinkers with the intervening sinker loops only and causing the sinker loops to pass from the backs to the throats of the sinkers over the tops of the nibs said steps occurring in each direction of reciprocatory knitting.

4. A method of knitting upon a circular, independent needle knitting machine which includes the steps of drawing a wrap yarn and a body yarn over the backs of the sinkers and through the needle loops of a previously knit course casting off the previously formed needle loops by engaging the sinkers with the intervening sinker loops only tightening the newly formed needle loops around the shanks of the needles below the

latches by stretching the newly formed sinker loops by causing them to pass from the backs to the throats of the sinkers over the tops of the nibs said steps occurring during reciprocatory knitting in each direction.

5. A method of knitting upon a circular, independent needle knitting machine which includes the steps of wrapping a yarn around a single needle drawing a body yarn over the backs of sinkers and knitting both yarns simultaneously in each direction of reciprocatory knitting.

6. A method of knitting upon a circular, independent needle, knitting machine which includes the steps of wrapping a yarn around a single needle drawing a body yarn over the backs of sinkers and knitting both yarns simultaneously in each direction of reciprocatory knitting of the instep.

7. A method of knitting upon a circular, independent needle, knitting machine which includes the steps of wrapping a yarn around a single needle, drawing a body yarn over the backs of sinkers and knitting both yarns simultaneously through the needle loops of the previous course, casting off the previously formed needle loops by engaging sinkers with the intervening sinker loops only and causing the sinker loops to pass from the backs to the throats of the sinkers over the tops of the nibs said steps occurring in each direction of reciprocatory knitting.

8. A method of knitting upon a circular, independent needle, knitting machine which includes the steps of wrapping a yarn around a single needle, drawing a body yarn over the backs of sinkers and knitting body yarns simultaneously through the needle loops of the previous course, casting off the previously formed needle loops by engaging sinkers with the intervening sinker loops only and causing the sinker loops to pass from the backs to the throats of the sinkers over the tops of the nibs said steps occurring in each direction of reciprocatory knitting of the instep.

9. A method of knitting split foot work upon a circular, independent needle, knitting machine which includes the steps of wrapping a yarn around a single needle drawing a body yarn over the backs of sinkers and knitting both yarns simultaneously in each direction of reciprocatory knitting.

OSCAR FREGEOLLE.
